UNITED STATES PATENT OFFICE.

WILLIAM L. ADAMS, OF SOUTH PORTLAND, MAINE.

DESIGN FOR A STEERING-WHEEL.

No. 87,810.

Specification for Design.

Patented Feb. 6, 1906.

Application filed November 18, 1905. Serial No. 288,080. Term of patent 7 years.

To all whom it may concern:

Be it known that I, WILLIAM L. ADAMS, a citizen of the United States, residing at South Portland, in the county of Cumberland and State of Maine, have invented a new, original, and ornamental Design for Steering-Wheels, of which the following is a specification, reference being had to the accompanying drawings, forming part thereof.

Figure 1 is a plan, and Fig. 2 a side eleva-

tion, of a steering-wheel, showing my new design.

I claim—

The ornamental design for a steering-wheel, as shown.

WILLIAM L. ADAMS.
